FABRIC TAKE-UP AND TENSION MEANS FOR
CIRCULAR KNITTING MACHINESRaymond H. Carhart, Philadelphia, Pa., assignor
to H. Brinton Co., Frankford, Philadelphia, Pa.,
a corporation of Pennsylvania

Application January 21, 1944, Serial No. 519,174

4 Claims. (Cl. 66—149)

1

My invention relates to combined fabric take-up and tension means for circular knitting machines, the same being directed mainly to knitting machines of the type having a stationary needle cylinder and a rotary cam ring, but not necessarily limited to that type, and it is an object of the invention to provide means of the character indicated, which shall be simple and inexpensive in construction, positive in operation, and not liable to get out of order.

Another object is to provide in one unit a fabric take-up, a tension control, and a fabric reel, all located underneath the machine so as to require no additional floor space, and where at the same time it is readily accessible.

Various devices have been proposed for maintaining a fabric under tension while being knitted, and for winding or otherwise collecting the fabric during the knitting operation. Thus it has been proposed to provide, in circular knitting machines of the stationary needle cylinder type, take-up tension rollers below the cylinder in combination with a reel located off to one side of the machine. An important objection to this is the excessive floor space required. Another familiar expedient is to provide such rollers close to the bottom of the needle cylinder, the cloth being permitted to accumulate beneath the machine, either in a basket or the like, or directly on the floor, and being cut off and removed at suitable intervals. This is quite unsuitable for wide fabric such as knitted on body machines, though used for narrow fabrics, such as string-work hosiery. Other expedients have been proposed, but are open to various objections, one of the principal objections to many such devices being that the machine must be stopped whenever fabric is removed therefrom. Another object of my invention therefore is to provide simple and easily operated means for removal of either a full wound roll of cloth or a partially filled roll.

Another object of my invention is to provide combined fabric tensioning and reeling means directly underneath the needle cylinder of a circular knitting machine, so constructed and arranged that the machine can knit continuously and that a filled or partly filled roll of cloth can be removed without stopping the machine.

Another object of the invention is to maintain a close control on the tension of the cloth being knitted.

Another object of the invention is to wind the cloth on a roll in such manner as to make an exceptionally uniform mass of cloth, evenly laid

2

and with square ends, the shape of such a roll being due largely to the closely controlled tension and to the use of effective means for holding the tubular fabric in well-spread-out position as it approaches the cloth roll.

Another object is to provide reeling means such that the roll of fabric will automatically remove itself from the machine when the roll of cloth reaches a predetermined diameter.

Still another object is to provide reeling means so constructed and arranged that the periphery of the roll of cloth approaches the floor as the roll grows larger, whereby the roll becomes easier to handle as it increases in size and weight.

since length of the lifting and lowering movements necessary to remove it from the machine and to place it on the floor or other support decreases with increasing size of the cloth roll.

Referring to the drawings, which are made a part of this application and in which similar reference characters indicate similar parts:

Fig. 1 is a perspective of the lower portion of a circular knitting machine having my improved take-up applied thereto.

Fig. 2, a side elevation of the take-up, viewed from the right in Fig. 1.

Fig. 3, a rear elevation of the take-up, with parts omitted.

Fig. 4, a detail view, showing on a larger scale certain parts also shown in Fig. 2.

Fig. 5, a section on line 5—5 of Fig. 2, showing gearing forming part of the invention.

Fig. 6, a section on line 6—6 of Fig. 4.

Fig. 7, a detail illustrating the relative positions of eccentrics at opposite sides of the machine for driving the take-up, and

Fig. 8, a section on line 8—8 of Fig. 3.

In the drawings, reference character 10 indicates generally the base-plate of a circular knitting machine in which there is knitted a fabric indicated at 11, which is wound on a fabric roll 12 to form a wound mass 13.

The roll 12 is provided at its ends with gudgeons 14 that are adapted to travel along inclined flanges 15 projecting inwardly from brackets 16 forming parts of, or secured to, the main frame 10. Slots in the brackets can, of course, be substituted for the flanges 15, if preferred. It will be evident that the roll of cloth can easily be lifted out of the machine when desired and an empty fabric roll 12 can be moved down along flanges 15 to the lowermost position, indicated in dotted lines in Fig. 8, to be filled in the subsequent operation of the machine. When the roll of cloth becomes of sufficient size so that the

gudgeons ride over the ends of the flanges 15, 15, the entire wound mass will automatically roll out on the floor and can then be separated from the cloth remaining in the machine and replaced by an empty fabric roll.

The cloth is guided in its path from the needles to the take-up roll by means of cloth guides, such as the pairs of guide rollers at 17 and 20. A spacer 18 is shown as connecting the brackets 16, but it has no guiding function.

For driving the fabric roll I provide means including a friction roller 21 against which the fabric roll bears as shown in Fig. 2, this roller being driven from a shaft 22, which may be the main shaft of the machine, by means of an eccentric 23, a connecting rod formed in two parts 24 and 25, and a pawl and ratchet mechanism operated by said rod. The two parts of the connecting rod are yieldingly connected by means including abutments 26 and 27, clamped to the upper member 24 by screws 29, 29, said abutments being slideable on the lower member 25, a collar 28 fixed to the lower rod member 25, and a spring 30 on said member 25 between the abutment 27 and collar 28. Preferably the abutment 26 is fixed in place, as by pinning it to rod section 24, whereas the abutment 27 is adjustable up and down on said rod section, the screw 29 acting as a set screw, or a rivet being substituted for it.

It will be evident that when the rod section 24 moves downward the abutment 26 will move without any effect on the rod member 25 until abutment 26 strikes collar 28, after which the rod member and parts operated thereby will be actuated positively, whereas on the return stroke the upper member moves positively with the eccentric but only lifts the lower member yieldingly through the spring 30 after the spring has been compressed sufficiently for the purpose. Thus a full stroke of the pawl may rotate the fabric roll through only a small arc, or even not at all, depending on the tension of the forming fabric and the position of the abutment 27 with reference to the spring 30.

The pawl and ratchet mechanism at the side of the machine shown in Fig. 2 comprises an oscillatory lever 31 carrying a pawl 32 forced by a spring 33 toward a ratchet 34, and a holding pawl 35 serves to hold the ratchet against reverse movement. Suitable means for idling the pawls is provided, being here shown as including a disk 36 at each side of the machine, said disks being suitably notched to expose parts of the ratchets for engagement by the pawls 32 and 35 when the take-up is to operate, but arranged to lift both pawls out of active position at desired times, as when it is necessary to turn the roller 21 backward manually to release the tension on the cloth; e. g., when the cloth is first put on the machine, or for convenience in replacing the cloth on the needles after a press-off. For this purpose the disks 36 are rotated manually by means of bars 37 having hand grips at a convenient height and extending down through guides 38 on the frame to their pivotal connection with the disks 36. The bars have pins 37'' adapted to enter either of a pair of holes in the adjacent side member 16, as best shown in Figure 1, showing the position of the parts when a pin 37'' has been entered in the lower one of two such holes. The roller 21 is covered with emery to cause it to grip the cloth on the fabric roll, and so is another roller 40 underneath which the cloth passes prior to its engagement by the fabric roll 21, i. e., both rollers 21 and 40 are

drive rollers for taking up and tensioning the cloth. The roller 40 aids in tensioning the fabric evenly and firmly and in guiding the same to the fabric roll. Roller 40 is driven in constant relation with roller 21 by means of meshing gears 41, 42, on the respective rollers.

In order to maintain a close control on the fabric it is desirable to provide for stepping the fabric roll around between impulses received from that pawl and ratchet means which is best shown in Fig. 2, and therefore I have provided an additional pawling means at the other end of the fabric roll, as shown in Figs. 1, 3 and 7, this including another pawling means having a pawl 32' on a lever 31' operated by links 24', 25' from an eccentric 23' which is set at an angle of 180° from the first-named eccentric, so as to rotate the fabric roll stepwise while the pawl 32' is being moved down preparatory to re-engagement with the ratchet. The parts for the second operating means (best shown in Fig. 1) are otherwise identical with those of the first operating means except that the pawls appear in reverse position as seen in said figure, being operated by a shaft 22' that is driven by gear connections to the cam ring, or in some other convenient manner, and therefore no further or more specific description is deemed necessary.

In the enlarged view of Fig. 8, cloth spreaders 45 and 46 are shown as arranged immediately above the respective pairs of guide rollers 17 and 20. The use of such spreaders is not new in itself, but by using two spreaders in succession above each of two pairs of guide rollers it is found that the roll of cloth is caused to be shaped very accurately, with square shoulders and flat ends, whereby the roll retains its shape, and whereby any wrinkles and the like are avoided in the cloth on the roll. The spreaders are shown as being made of wood, but metallic spreaders may be used. They may also be omitted, as in Fig. 2, but such omission is undesirable.

It will be evident that the roll of fabric may ride over the ends of the guides 15, 15 when the roll reaches a predetermined diameter, all without danger of injury to the cloth or of changing the shape of the roll detrimentally, since the periphery of the roll is close to the floor, and in fact is closer to the floor when the roll is full than at the beginning of the operation or at any intermediate stage in the winding. It is easy also to remove the fabric roll from the machine at any stage of the winding, since there is nothing to uncouple or to be dismounted or disengaged, and nothing to interfere with removal of the roll. Although the wound mass of cloth does not project to any considerable extent beyond the machine frame even when the cloth roll is full and about to roll off the tracks 15, it can obviously be reached easily by men standing near the machine for the purpose of lifting the roll out of the machine.

It will be obvious to those skilled in the art that many changes may be made in the devices herein disclosed, all without departing from the spirit of the invention; and therefore I do not limit myself to what is shown in the drawings and described in the specification, but only as indicated in the appended claims.

Having thus fully described my invention, what I claim is:

1. In a knitting machine, a take-up for the forming fabric comprising a fabric roll, a roller in frictional engagement with said fabric roll, pawl and ratchet means at each end of said fabric

roll for driving said roller, the driving pawl of each of said means being constructed and arranged to act on said roller while the other driving pawl is making its return stroke.

2. A circular knitting machine comprising a table, legs supporting the table, brackets at opposite sides of the table and each located between a pair of legs, inclined tracks on said brackets extending upward and forward to the respective front legs of said pairs, a drive roller adjacent the lower ends of said tracks for driving a cloth roll located on said tracks, the relation of such parts being such that the periphery of the cloth wound on the cloth roll approaches the floor as the roll increases in size.

3. In a circular knitting machine having a stationary needle cylinder, the combination of inclined tracks at opposite sides of the machine,

said tracks leading upward and toward one side of the machine, a fabric roll underneath the needle cylinder and supported by said tracks, and means for driving the fabric roll in timed relation with the operation of the machine, said tracks being constructed and arranged so that the fabric mass will roll off the tracks and onto the machine supporting floor when the mass reaches a predetermined size, and the driving means being so arranged and constructed with respect to the roll and the tracks that the periphery of said mass approaches closer to the floor as the mass approaches such predetermined size.

15 4. A device as in claim 1, including independent manually-operable means for inactivating either or both of said pawls.

RAYMOND H. CARHART.
